PNEUMATIC SOLE FOR SHOES

Frank Guild, Mount Kisco, N. Y.

Application April 7, 1934, Serial No. 719,462

10 Claims. (Cl. 36—29)

This invention relates to new and useful improvements in a pneumatic sole for shoes.

The invention has for an object the construction of a pneumatic sole which is characterized by a full sole and a half sole disposed upon the front of the full sole and having a central cutout area, and a rubber tube rolled in spiral shape within the central cutout area.

Still further the invention proposes an arrangement wherein a passage connects the central cutout area to the inner end of the half sole, and wherein the rubber tube has one end extended through said passage and provided with a valve arranged over an opening in the full sole.

Still further the invention also proposes the provision of means for closing the opening in the full sole operative to expose the opening so that the valve may be reached.

Another one of the objects of this invention is the arrangement of novel means for holding the rubber coil within said central cutout area.

Still further the invention proposes the provision of an adhesive tape engaged across the top of the central cutout area and engaging the spiral coil rubber tube for holding the rubber tube in position while permitting the transfer of resilient action from above the sole to the rubber tube.

Still further the invention also proposes an arrangement whereby the rubber tube may be shifted within the central cutout area after the sole is upon a shoe so as to better suit the comfort of one's foot.

Still further the invention proposes the provision of an endless ribbon connected at one area with a portion of the coil and adapted to be shifted from the outside for shifting the coil.

Still further the invention proposes the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a plan view of a pneumatic sole for shoes according to this invention.

Fig. 2 is a sectional view taken on the line 2—2 of Fig. 1.

Fig. 3 is a fragmentary enlarged detailed view

of a portion of Fig. 2 showing in particular the construction of the means for closing the opening in the full sole.

Fig. 4 is a plan view similar to Fig. 1 but illustrating another embodiment of the invention. 30

Fig. 5 is a sectional view taken on the line 5—5 of Fig. 4.

Fig. 6 is another plan view similar to Fig. 1 but illustrating a further modification of the invention. 65

Fig. 7 is a sectional view taken on the line 7—7 of Fig. 6.

The pneumatic sole for shoes according to this invention comprises a full sole 10 including a heel portion 11. A half sole 12 is disposed upon the front of the full sole and has a central cutout area 13 with a passage 14 connecting this area with the inner end 15 of the half sole. This inner end 15 of the half sole is formed with a bevel as clearly illustrated in Figs. 75 1 and 2 so that there is no abrupt change of surface in the sole.

A rubber tube 16 is wound and formed into spiral shape and has a closed end 16' and is disposed within the cutout area 13 and has an 80 outer end 16" equipped with a valve 17. The valve 17 is located over an opening 18 in the full sole. This opening is shown to comprise a tubular member 19 engaged through the sole and having a detachable plug 20 screwed into 85 its bottom end. The valve 17 is of conventional construction and therefore its detail will not be disclosed. The valve is of the type generally used upon bicycle tubes and the inner tubes of automobile tires. More particularly the valve 90 is of the type to allow air to enter the tube but to automatically restrain this air from discharging unless a small stem within the valve itself is moved to open the valve. A short line of stitches 22 connects the front ends of the 95 full and half soles.

It is intended that the sole be attached upon a shoe upper and constitute the sole of the shoe. The feature of the invention is that the ball of the foot will engage against the rubber tube and so relieve strains due to walking, running, etc.

In Figs. 4 and 5 another embodiment of the invention has been disclosed in which an arrangement is provided for holding the spiral coil tube 16 in a fixed position within the central opening 13. This means comprises several strips of adhesive tape 22 pasted across the top of the half sole 12. The ends of the tape are 110

attached upon the area of the half sole outside of the central cutout area 13. The tapes are shown crossing each other. With this arrangement the resiliency of the spiral rubber tube is transmitted to the ball of the foot since the tapes are flexible, but at the same time the tapes function to hold the coil in a stationary position. In other respects this form of the invention is identical to the previous form and corresponding part may be recognized by the same reference numerals.

In Figs. 6 and 7 another modification of the invention has been disclosed in which provision is made for adjusting the position of the spiral rubber tube from the outside of the sole when desired. This means comprises an endless band 23 of flexible material such as cloth extended transversely across the top of the half sole and extended down the sides and in a groove 24 between the full and half soles. A peg 25 projects from the upper portion of the band 23 and is attached to the inner end 16' of the rubber tube. The arrangement is such that the position of the band 23 may be shifted around the half sole for the purpose of shifting the position of the peg 25 and similarly shifting the rubber tube. When this sole is attached upon a shoe it should be attached to the bottom side of an extra outer sole layer so that the shoe can be water tight even though the band 23 may be shifted. To shift the band 23 it must be gripped on opposite sides of the sole. This is possible, for example, by engaging needles or similar implements through the exposed portion. After shifting has been accomplished the needles should be withdrawn.

It is to be understood that the pneumatic soles may be of any size to fit men's, women's or children's shoes.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A pneumatic sole for shoes, comprising a full sole including a heel portion, a half sole disposed upon the front of said full sole and having a central cutout area, with a passage connecting with the inner end of the half sole, and a rubber tube with a closed end and in spiral form within said central cutout area and having its other end extending through said passage and equipped with an air valve and disposed over an opening in said full sole.

2. A pneumatic sole for shoes, comprising a full sole including a heel portion, a half sole disposed upon the front of said full sole and having a central cutout area, with a passage connecting with the inner end of the half sole, and a rubber tube with a closed end and in spiral form within said central cutout area and having its other end extending through said passage and equipped with an air valve and disposed over an opening in said full sole, the inner edge of said half sole being formed with a tapered edge.

3. A pneumatic sole for shoes, comprising a full sole including a heel portion, a half sole disposed upon the front of said full sole and having a central cutout area, with a passage

connecting with the inner end of the half sole, and a rubber tube with a closed end and in spiral form within said central cutout area and having its other end extending through said passage and equipped with an air valve and disposed over an opening in said full sole, said soles being secured together with stitches.

4. A pneumatic sole for shoes, comprising a full sole including a heel portion, a half sole disposed upon the front of said full sole and having a central cutout area with a passage connecting with the inner end of the half sole, and a rubber tube with a closed end and in spiral form within said central cutout area and having its other end extending through said passage and equipped with an air valve and disposed over an opening in said full sole, and means for closing the opening in said sole.

5. A pneumatic sole for shoes, comprising a full sole including a heel portion, a half sole disposed upon the front of said full sole and having a central cutout area with a passage connecting with the inner end of the half sole, and a rubber tube with a closed end and in spiral form within said central cutout area and having its other end extending through said passage and equipped with an air valve and disposed over an opening in said full sole, and means for closing the opening in said sole, comprising a tubular member engaged through the sole, and a plug detachably engaged in the end of the tubular member.

6. A pneumatic sole for shoes, comprising a full sole including a heel portion, a half sole disposed upon the front of said full sole and having a central cutout area, with a passage connecting with the inner end of the half sole, a rubber tube with a closed end and in spiral form within said central cutout area and having its other end extending through said passage and equipped with an air valve and disposed over an opening in said full sole, and adhesive tape engaged across the upper face of said half sole for holding the rubber tube in position.

7. A pneumatic sole for shoes, comprising a full sole including a heel portion, a half sole disposed upon the front of said full sole and having a central cutout area, with a passage connecting with the inner end of the half sole, a rubber tube with a closed end and in spiral form within said central cutout area and having its other end extending through said passage and equipped with an air valve and disposed over an opening in said full sole, and adhesive tape engaged across the upper face of said half sole for holding the rubber tube in position, the ends of the adhesive tape being secured upon the area of the half sole to the sides of the central cutout area.

8. A pneumatic sole for shoes, comprising a full sole including a heel portion, a half sole disposed upon the front of said full sole and having a central cutout area with a passage connecting with the inner end of the half sole, a rubber tube with a closed end and in spiral form within said central cutout area and having its other end extending through said passage and equipped with a valve and disposed over an opening in said full sole, and means for shifting the position of the spiral coil rubber tube from the outside of the sole.

9. A pneumatic sole for shoes, comprising a full sole including a heel portion, a half sole disposed upon the front of said full sole and having a central cutout area with a passage
